UNITED STATES PATENT OFFICE.

LEONARD STUDY, OF McPAUL, IOWA.

HARVESTER-CUTTER.

SPECIFICATION forming part of Letters Patent No. 351,004, dated October 19, 1886.

Application filed January 6, 1886. Serial No. 187,808. (No model.)

To all whom it may concern:

Be it known that I, LEONARD STUDY, a citizen of the United States, residing at McPaul, in the county of Fremont and State of Iowa, have invented certain new and useful Improvements in Harvester-Cutters; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to cutting apparatus for reaper and mowing machines; and it consists in combining therewith an attachment to prevent the rear edge of the cutter-bar and the front edge of the finger-bar from rubbing together, thereby reducing the friction and the wear of the parts, by which a lighter draft is secured.

The object of the invention is to secure a parallel motion of the cutter-bar during its reciprocating movement and prevent the rear edge engaging with the finger-bar.

To these ends it consists in the novel features hereinafter more fully set forth and claimed.

In the drawings, Figure 1 is a plan view of a cutting apparatus provided with my attachment, parts being broken away to show its construction. Fig. 2 is an inverted plan view of the case with the operating parts in position. Fig. 3 is a perspective detail of a portion of the cutting apparatus and one end of the case, showing the means for fastening it in place; and Fig. 4 is a similar view showing the opposite side of the case and the means by which it is held in place.

The fingers *a*, finger-bar *A*, and cutter-bar *B* are of ordinary construction and operation. A case, *C*, secured to the finger-bar, projects over the cutter-bar and holds the latter in close relationship with the finger-bar. Lugs *c*, projecting from one side of the case, pass under and engage lugs *d* of a casting, *D*, secured to the finger-bar, and a lug, *c'*, extending from the opposite side, is engaged by a catch, *E*, pivoted to the finger-bar. The lug *c'* fits in between the posts *e* and *e'*, and the catch or lever *E* is pivoted at one end to the

post *e*, and its other end is adapted to fit into a groove, *e'*, cut in the post *e*. By these devices the case and attachment are securely held in place. The levers are extended beyond the posts *e*, as shown, to present a handle to be grasped when operating them to remove or secure the cases in place.

Within the case, on each side, a rod or bar, *F*, is pivoted at *f*, and the free ends of such rods are pivotally connected to a link, *G*, which should have an expanded end, so that the points of attachment between it and the rods *F* shall be at a distance apart, as shown at *g*. The free end of the link is pivotally connected with the cutter-bar *g'*.

The rods or bars *F* and *G* are so disposed that the free end *g'* of the link moves in a straight line, always remaining parallel to a line passed transversely through the normal position of said end or point *g'*. In practice the end *g'* is bent at right angles to the link and enters an opening, *b*, in the cutter-bar. It is evident that as many of these attachments may be provided as is necessary, and that they may be located at any point or points found most convenient.

It must be observed that the length of the rods or bars *F* is equal to the distance between the points *g* and *g'*; also that the rods incline or gradually approach each other from the points *f* to their pivotal connections with the link. The points *f* are fixed relative to the finger-bar and the point *g'* fixed relative to the cutter-bar. In the operation of the latter the bars *F* are vibrated about the points *f*, and the distances between the points *f* and the point *g'* vary proportionally to the inclination of the rods in such a manner as to cause the point *g'* to move in a straight line, which at all times will be parallel to a line drawn through or between the points *f*.

While the case is shown attached to the finger-bar, it is evident that the parts may be reversed without departing from the spirit of my invention.

Having thus described my invention, what I claim, and desire to secure by Letters Patent, is—

1. The combination, with a finger-bar and cutter-bar, of a pair of rods or bars pivoted on the finger-bar, and a link pivotally connecting

the two and pivoted to the cutter-bar, whereby the cutter-bar is steadied in its longitudinal movement and the abrasion between its rear edge and the front edge of the finger-bar reduced, substantially as and for the purposes set forth.

2. The combination of the finger-bar, the cutter-bar, a case removably secured to the finger-bar and overhanging and bearing upon the cutter-bar to hold it close upon the finger-bar, a pair of bars or rods, each pivotally connected at one end to the case, and a link uniting the free ends of the bars and pivotally connected with the cutter-bar, substantially as shown and described.

3. The combination, with the finger and cutter bars, the pair of rods and a link pivotally connected at one end with the adjacent ends of the rods, of a case inclosing the rods and link, provided with lugs *c* and the lug *c'*, the casting *D*, having lugs to engage lugs *c*, and a catch to contact with lug *c'*, whereby the bars, link, and cutter-bar are removably held in place, substantially as set forth.

In testimony whereof I affix my signature in presence of two witnesses.

LEONARD STUDY.
